UNITED STATES PATENT OFFICE.

CHARLES A. BARTLETT, OF CAPE BRETON, NOVA SCOTIA, CANADA.

OIL-CAN.

1,211,043.

Specification of Letters Patent.

Patented Jan. 2, 1917.

Application filed April 20, 1915. Serial No. 22,723.

To all whom it may concern:

Be it known that I, CHARLES A. BARTLETT, a subject of the King of Great Britain, residing at Cape Breton, in the Province of Nova Scotia, Dominion of Canada, have invented certain new and useful Improvements in Oil-Cans; and I do hereby declare the following to be a full, clear, and exact description of the invention, such as will enable others skilled in the art to which it appertains to make and use the same.

This invention relates to improvements in oil cans.

One object of the invention is to provide an oil can of such construction that the filling and spout openings can be effectively closed so as to prevent the escape of liquid should the can be turned over.

Another object of the invention is to provide novel closure means for the filling and spout openings which can be operated independently of each other when the can is to be filled or liquid to be discharged therefrom.

Other objects and advantages will be apparent from the following description when taken in connection with the accompanying drawing, in which:

Figure 1 is an elevation of a can made in accordance with my invention, Fig. 2 is a top plan view, Fig. 3 is a section on the line 3—3 of Fig. 1, the filling and spout closures being shown in dotted lines as swung out of normal position, and Fig. 4 is a section on the line 4—4 of Fig. 2.

Referring particularly to the accompanying drawing, 10 represents the body of the oil can which is formed with an upwardly tapering top 11 in the upper end or apex 40 of which is formed a vertical flange 12 surrounding the filling opening. In the lower portion of the top is a spout 13, the upper end of which is held in proper position by a brace 14 extending between and connected 45 to the spout and to the top. Threaded into the upper side of the brace is a vertically ex-

tending bolt 15 on which bolt are rotatably mounted the pair of arms 16 and 17. The former of the arms, 16, carries a rubber plug 18 which is removably engaged in the end 50 of the spout, while the end of the arm 17 carries a rubber stopper or plug 19 for engagement in the filling opening. This bolt has a milled head 20 on the upper end by means of which the same can be rotated 55 and below the head is a sleeve 21 which bears on the inner ends of the arms 16 and 17 so as to hold them in such position that the stoppers carried thereby will be firmly wedged in the filling opening and spout. 60 At the opposite side of the top is a vertically extending tube 22 secured on the inclined wall of the top and over a small opening 23 made through the top. A guide 24 is disposed slidably in this tube and carries a 65 stem 25 which extends down into the can, the lower end of the stem being provided with a float 26. Suitable marks are formed on this stem which become exposed successively as the can is being filled so that it 70 can be readily ascertained when the can is full. The can is also provided with a suitable bail 27.

What is claimed is:

In an oil can a body having an upwardly 75 tapering top provided with a filling opening in the apex thereof, a spout, a brace connected to the top and spout, a vertical thumb screw engaged in the brace, a pair of arms rotatably mounted on the screw, stoppers 80 carried on the outer ends of the arms for disposition respectively in the filling opening and spout, and a sleeve on the screw for engagement with the inner ends of the arms to clamp the stoppers in the filling opening 85 and spout.

In testimony whereof, I affix my signature, in the presence of two witnesses.

CHARLES A. BARTLETT.

Witnesses:

ERNEST OAK,
JOSEPH ALLISON.
